UNITED STATES PATENT OFFICE.

HOWARD G. CONNELL AND ALBERT J. SWINDALL, OF DRYAD, WASHINGTON.

CATTLE-GUARD.

1,344,262.

Specification of Letters Patent. Patented June 22, 1920.

Application filed March 3, 1919. Serial No. 280,363.

To all whom it may concern:

Be it known that we, HOWARD G. CONNELL and ALBERT J. SWINDALL, citizens of the United States, residing at Dryad, in the 5 county of Lewis, State of Washington, have invented certain new and useful Improvements in Cattle-Guards; and we do hereby declare the following to be a full, clear, and exact description of the invention, such as 10 will enable others skilled in the art to which it appertains to make and use the same.

This invention relates to new and useful improvements in guards and particularly to cattle guards for railways.

15 One object of the present invention is to provide a novel and improved device of this character which will move when an animal steps thereon and which will automatically be restored to normal position when the 20 animal removes itself therefrom.

Another object is to provide a novel and improved device of this character which is capable of being installed on the railway without modifications thereto.

25 Other objects and advantages will be apparent from the following description when taken in connection with the accompanying drawing.

In the drawing:

30 Figure 1 is a top plan view of the improved cattle guard in position on the railway.

Fig. 2 is an enlarged vertical transverse sectional view taken on the line 2—2 of 35 Fig. 1.

Fig. 3 is a sectional view taken on the line 3—3 of Fig. 1, longitudinally of the railway, and enlarged.

Fig. 4 is a bottom plan view of the device.

Referring particularly to the accompanying drawing, 10 represents the ties of the railway, and 11 the rails thereof. Carried by the ends of two adjacent ties are the 45 depending brackets 12, and supported in these brackets and extending between said ties are the metal track bars 13. Disposed longitudinally between the ties are the two beams 14, and 15, the former being normally close to the adjacent tie while the latter is normally a suitable distance from the other tie. Supported in brackets on the lower faces of the ends of the said beams are the grooved rollers or wheels 16 which 50 run on the before-mentioned track bars 13. A plurality of spacing and bracing strips 55

17 are secured to the upper faces of the beams 14 and extend therebetween, as clearly seen in the drawing. The upper faces of the beams are disposed in the same plane 60 as the upper faces of the ties, and to accommodate the rail bases there are formed therein notches or recesses 18 lined with sheet metal strips 19 to prevent excessive wear of the walls of said recesses as the 65 guard moves beneath the rails. Secured to the upper faces of the strips 17, and extending transversely between the rails, are the metal guard blades 20. It will be noted that the ends of the blades are spaced from 70 the rails to permit the flanges of the car wheels to escape the said ends. Secured to the strips 17, and extending outwardly from the outer sides of the rails, are the shorter guard blades 21. 75

Connected to one of the ties, at one end, and at their other ends to the adjacent beam 14, are the strong springs 22 which normally hold the entire structure close to the said tie, but when an animal steps on the guard 80 the device will move on the track bars against the tension of the springs. When the animal feels itself moving it will draw back and get off the guard. Immediately that the animal gets off the guard the 85 springs 22 draw the guard back into normal position adjacent the tie to which the springs are attached. Also certain of the ties may carry buffer springs 23 to reduce the shock when the structure is moved 90 quickly to an extreme position.

There is thus provided a novel and improved device which will effectively keep animals from railways.

What is claimed is:

1. A railway cattle guard comprising tracks supported by and between certain ties parallel with the rails, a frame structure having wheels movably mounted on said tracks, and blades carried by the structure between and outside the rails. 95

2. A railway cattle guard comprising tracks supported by and between certain contiguous ties, two beams underlying the rails and overlying said tracks and having 105 wheels traveling on the latter, strips connecting the beams and movable with them longitudinally of the railway, and blades mounted on the strips.

3. A railway cattle guard comprising 110 brackets on contiguous faces of pairs of adjacent ties, tracks connecting said brackets

ets and standing parallel with and below the line of the rails, beams between the ties of each pair movably mounted on said tracks and underlying the rails and notched 5 beneath the latter, strips connecting said beams, and blades carried by the strips.

4. A railway cattle guard comprising tracks supported between pairs of contiguous ties parallel with and below the line of 10 the rails, transverse beams underlying the rails between the ties of each pair and having wheels traveling on said tracks, strips supported by the beams, and blades carried by the strips.

15 5. In a railway cattle guard, the combination with tracks paralleling the rails between contiguous ties, a frame structure including beams having wheels movable on said tracks, and blades carried by such

structure; of springs holding said guard at 20 one limit of its movement.

6. In a railway cattle guard, the combination with tracks paralleling the rails between contiguous ties, a frame structure including beams having wheels movable on 25 said tracks, and blades carried by such structure; of buffer springs for cushioning the movement of said guard to one extreme limit, and yielding means for holding it at one extreme.

30 In testimony whereof, we affix our signatures in the presence of two witnesses.

HOWARD G. CONNELL.

ALBERT J. SWINDALL.

Witness as to Howard G. Connell:

Mrs. A. C. MOORE.

Witness as to Albert J. Swindall:

NANCY TAYLOR STIDHAM.
